UNITED STATES PATENT OFFICE.

LOUIS C. LOEWENSTEIN, OF LYNN, MASSACHUSETTS, ASSIGNOR TO GENERAL ELECTRIC COMPANY, A CORPORATION OF NEW YORK.

DISCHARGE-VANES FOR CENTRIFUGAL COMPRESSORS.

1,085,274.

Specification of Letters Patent. Patented Jan. 27, 1914.

Application filed July 31, 1912. Serial No. 712,495.

To all whom it may concern:

Be it known that I, LOUIS C. LOEWENSTEIN, a citizen of the United States, residing at Lynn, county of Essex, State of Massachusetts, have invented certain new and useful Improvements in Discharge-Vanes for Centrifugal Compressors, of which the following is a specification.

This invention relates to centrifugal compressors, and its object is to provide an improved mode of securing the discharge vanes in position.

The principal point aimed at is to get rid of rivets and any form of support in the passages between the vanes so that there is no interference with the flow of air, especially at the beginning where the velocity is highest.

Other ends in view are the prevention of vibration and noise, the maintenance of the vanes in accurate positions, and the lessening of cost of construction.

To accomplish these results, I mount the vanes in grooves in the side plates of the diffuser, the side edges of the vanes being preferably chamfered off and the grooves made slightly V-shaped to insure a tight fit. Near the outer end of each vane a transverse bolt or rivet is inserted to hold the side plates together and also to secure the vane in position.

In the accompanying drawing, Figure 1 is a section of a portion of a centrifugal compressor showing my improved discharge vanes in position; Fig. 2 is a cross section of the diffuser on a larger scale, taken on line 2-2, Fig. 1; Fig. 3 is a section along one of the vanes on a smaller scale; and Fig. 4 is a similar section showing a modified construction.

The annular side plates 1,2 of the diffuser are provided with a plurality of eccentric grooves 3, which may be conveniently cut on a boring mill. In cross section, these grooves are preferably tapered or V-shaped, as shown at 4 in Fig. 2, though a groove with parallel walls may be used if desired, as shown at 5.

The discharge vanes 6 have their side edges received in the grooves 3, said edges 50 being either chamfered or not according to the shape of the grooves in which they are inserted. Near the outer end of each vane, where it will interfere least with the flow of air, is a stout rivet 7 whose ends pass 55 through the side plates 1, 2 and are peened over, as shown. The rivets serve not only to connect the side plates but also to support the vanes, being flattened on their under sides to fit the surface of the vanes. Rivets 60 secure the vanes to the rivets 7.

Instead of a continuous groove, I may form a series of short grooves, recesses or depressions in the side plates to receive tongues 9 on the edges of the vanes 10 as 65 shown in Fig. 4. These vanes may be secured to the transverse rivets 7, as in the structure shown in the other figures of the drawing.

It will be apparent that the several objects aimed at, as enumerated above, are attained by the construction which I have disclosed.

In accordance with the provisions of the patent statutes, I have described the principle of operation of my invention, together with the apparatus which I now consider to represent the best embodiment thereof; but I desire to have it understood that the apparatus shown is only illustrative, and that 80 the invention can be carried out by other means.

What I claim as new and desire to secure by Letters Patent of the United States is,--

1. In a centrifugal compressor, a diffuser 85 having its side plates grooved, discharge vanes having their side edges received in said grooves, and members extending transversely between said side plates adjacent the vanes and secured thereto.

2. In a centrifugal compressor, a diffuser having its side plates provided with grooves V-shaped in cross section, discharge vanes having chamfered side edges received in said grooves, and transverse rivets connecting 95 said side plates and each secured to a vane.

3. In a centrifugal compressor, a diffuser having its side plates grooved, discharge vanes having their side edges received in said grooves, and a transverse rivet connecting said side plates near the outer end of each vane and secured to said vane.

In witness whereof, I have hereunto set

my hand this twenty ninth day of July, 1912.

LOUIS C. LOEWENSTEIN.
